CLAIM

The ornamental design for a lighting logo optical mouse, as shown and described.

DESCRIPTION

FIG. 1 is a front elevational view of a lighting logo optical mouse showing my new design.

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof; and,

FIG. 7 is a front elevational view thereof showing the lighting logo optical mouse being switched on.

The broken line showing portions of the lighting logo are included for information purposes only and form no part of the claimed design.
